UNITED STATES PATENT OFFICE.

ALBERT PAPENFUSS, OF ROCHESTER, NEW YORK.

ASH SIFTER.

Application filed December 30, 1926. Serial No. 158,093.

The object of this invention is to provide an improved ash sifter that can be readily mounted on an ash can so that the ashes when sifted drop directly into the ash can 5 while the pieces of unburned coal and large clinkers roll out at the end of the ash sifter and into a bucket attached to the ash sifter on the outside of the ash can.

This and other objects of this invention 10 will be fully illustrated in the drawing, described in the specification and pointed out in the claims at the end thereof.

In the accompanying drawing:

Figure 1 is a partial perspective and sectional view of the improved ash sifter and upper portion of an ash can on which the ash sifter is mounted.

Figure 2 is a detail perspective view of the removable sifting screen of the ash sifter.

Figure 3 is a detail perspective view of the removable hopper of the ash sifter.

In the several figures of the drawing like reference numerals indicate like parts.

The ash sifter forming the subject matter 25 of my present invention is of a type that can be readily mounted on an ash can and operated thereon so that the ashes sifted will drop directly into the can while the unburned particles of coal will roll out of the 30 ash sifter into a bucket attached to the side of the ash sifter on the outside of the ash can.

As illustrated in the drawing the ash sifter has for its base a flanged cover 1 which 35 telescopes over the ash can to firmly support the ash sifter thereon. In the center of the flanged cover 1 is provided a rectangular opening 2 on the two sides and one end of which are anchored suitable walls forming 40 part of the casing 1^A in which the sifting screen 3 is mounted. All but a small portion of the upper edge of each of the side walls is angular and between these angular edges of the side wall is supported the cover plate 45 4. This leaves a rectangular opening 5 in the top of the casing at the high end thereof in which the hopper 6 is supported. At the opposite or low end, the casing 1^A forms a rectangular nozzle 7 which overhangs the 50 cover base 1 and is provided with a hook 8 on which the bucket 9 may be suspended so as to be located below the nozzle 7 and receive the particles of coal or the larger clinkers that roll over the screen of the ash sifter and do not drop into the ash can.

As above pointed out the screen 3 of the

ash sifter is mounted within the casing located above the rectangular opening 2 in the cover base 1. This screen is oblong and is surrounded on the two sides and at one end by the flange 10. Reinforcing bars 11 and 12 are located on the under side of the screen 3 and are attached to the flange 10 to suitably support the screen at intervals of 65 its length.

To the closed end of the screen is attached the handle 13 which extends rearwardly of the flange surrounding the screen and passes thru the horizontal slot 14 provided in the vertical end wall of the housing 1^A surrounding the screen. In the open end of the screen 70 a flange 15 is attached to it and extends beyond it and in this flange is provided a hole 16 which is adapted to register with a corresponding hole 17 provided in the bottom of the nozzle end 7 of the casing 1^A surrounding the screen 3.

A cotter pin 18 or other suitable pivot pin is inserted thru the holes 16 and 17 thus pivoting the lower end of the screen into the nozzle end 7 forming part of 75 the casing surrounding the screen. The screen 3 is thus suspended at both ends within its casing. The casing 1^A in which the screen is suspended is considerably wider than the width of the screen so that the 80 screen may be moved laterally within it. As the lower end of the screen is pivotally fixed in the nozzle of the casing it is only the upper end that can be moved sideways. The horizontal slot 14 thru which the handle 13 90 of the screen extends is therefore long enough to allow this handle to be moved back and forth in order to give the screen an oscillating motion on its pivot pin 18.

The oscillating movement of the screen is 95 limited by the lower end of the hopper 6 which is supported and extends into the casing and projects between the flanges surrounding the screen 3. When the screen is oscillated, the inside of the flange 10 surrounding the screen 3 alternately makes contact with the outside of the opposing conical sides of the hopper 6 thus limiting the movement of the screen in either direction as well as slightly shaking the lower end of the hopper so that the ashes contained therein are kept in motion and cannot settle in any particular spot or bridge the whole of the inside of the hopper and prevent the ashes from dropping into the screen.

The hopper 6 is provided with a pair of holes 19 and 20 one on each side thereof

which holes are in line with corresponding holes provided in the casing 1^A so that a pin can be inserted into them and lock the hopper in place in the casing. To remove the hopper these pins are removed and when removed allow the hopper to be lifted out of the casing. A cover 21 is hinged to the top of the hopper so that the hopper can be closed after the ashes have been dumped into it and are being sifted into the ash can.

In the front wall of the hopper at the lower end thereof is provided the opening 22. The size of this opening is regulated by the gate 23 that is located within the hopper 6 and is suitably clamped in place to the inside of the front wall thereof by means of a bolt 24. In the gate 23 are provided a series of holes thru which the bolt 24 is adapted to pass and hold the gate at any desired elevation within the hopper in order to regulate the size of the opening thru which the larger pieces of clinkers and the unburned coal can pass and roll down over the screen into the bucket on the outside of the ash sifter. Thus a large or small space may be provided between the screen 3 and the top of the opening in the front of the hopper depending on the ashes to be sifted thru the ash sifter.

As above pointed out the hopper 6 is removable from the casing and this is also true of the screen 3. By simply removing the pivot 18 the screen is released so that it can be moved forward until the handle 13 has been moved out of the slot 14 after which the screen can be pulled out of the top of the casing through the opening from which the hopper has previously been removed.

I claim:

1. In an ash sifter for ash cans, the combination of a cover having an opening therein, an elongated rectangular casing having an opening at one end at the top thereof and an opening at the opposite end thereof, a screen, a flange surrounding said screen on two sides and one end thereof, a removable hopper adapted to engage into the opening in the top of said casing, and projecting between the flange surrounding said screen, means for oscillating said screen, said flange

of said screen being adapted to make contact with the outside of said hopper to vibrate said hopper at the end of each oscillation.

2. In an ash sifter for ash cans, the combination of a cover having an opening therein, an elongated rectangular casing having an opening at one end at the top thereof and an opening at the opposite end thereof, a screen, a flange surrounding said screen on two sides and one end thereof, a removable hopper adapted to engage into the opening in the top of said casing, and projecting between the flange surrounding said screen, means for oscillating said screen, said flange of said screen being adapted to make contact with the outside of said hopper to vibrate said hopper at the end of each oscillation, an adjustable gate at the bottom of said hopper a the front wall thereof said gate being adapted to provide a large or small opening between said screen and the bottom of said gate in the front wall of said hopper to allow large or small particles of coal or clinkers to pass therethrough.

3. In an ash sifter for ash cans, the combination of a cover having an opening therein, an elongated rectangular casing having an opening at one end at the top thereof and an opening at the opposite end thereof, a screen, a flange surrounding said screen on two sides and one end thereof, a handle provided on said flange at the end of said screen, an extension flange on the end of said screen not closed by said flange, said extension flange being pivoted in the opening at the end of said casing, said casing having a horizontal slot in the wall thereof at a point opposite to the opening in the end of said casing and at a higher elevation thereof, said handle of said screen being adapted to engage into said opening and support the end of said screen at an angle within said casing, said handle being adapted to be reciprocated within the horizontal slot in said casing to oscillate said screen on its pivoted end.

In testimony whereof I affix my signature.

ALBERT PAPENFUSS.
